United States Patent Office

Des. 179,079
Patented Oct. 30, 1956

179,079

END TABLE

Lawrence J. Hopper, South Bend, Ind.

Application September 30, 1954, Serial No. 32,492

Term of patent 3½ years

(Cl. D33—14)

FIG. 1.

FIG. 2.

FIG. 3.

FIG. 4.

Fig. 1 is a perspective view of an end table showing my new design;

Fig. 2 is a top perspective view of the end table;

Fig. 3 is a top plan view of the end table; and

Fig. 4 is a side elevation of the end table showing my new design.

I claim:

The ornamental design for an end table, as shown.
